TUMBLER OR SIMILAR ARTICLE

George L. Traner, Barrington, Ill., and Don A. Schreckengost, East Liverpool, Ohio, assignors to Royalon, Inc.,
Sebring, Ohio, a corporation of Ohio

Filed Apr. 6, 1964, Ser. No. 79,368

Term of patent 14 years

(Cl. D36—8)

FIG. 1.

FIG. 2

FIG. 1 is an elevation of a tumbler or similar article, showing our new design, and

FIG. 2 is a bottom view thereof.

The characteristic features of the design reside in the portions shown in full lines, comprising the combination of crackled finish and the particularly shaped clear cuts therein, in the pattern shown, it being understood that the ornamentation shown is continuous about the entire periphery of the tumbler body.

We claim:

The ornamental design for a tumbler or similar article, substantially as shown and described.
